UNITED STATES PATENT OFFICE.

MATIEU BOURHANOVSKY, OF LIBAU, AND ALEXANDRE DE KOWANKO,
OF ST. PETERSBURG, RUSSIA, ASSIGNORS OF ONE-THIRD TO AUGUST
POTOCKI, OF WARSAW, RUSSIA.

APPARATUS FOR RAISING SUNKEN SHIPS.

SPECIFICATION forming part of Letters Patent No. 691,713, dated January 21, 1902.

Application filed October 11, 1901. Serial No. 78,362. (No model.)

To all whom it may concern:

Be it known that we, MATIEU BOURHANOVSKY, residing at Libau, and ALEXANDRE DE KOWANKO, residing at St. Petersburg, 5 Russia, subjects of the Emperor of Russia, have invented certain new and useful Improvements in Apparatus for Raising Sunken Ships or other Objects, of which the following is a specification.

10 It is well known that sunken objects, such as ships, can be raised by connecting them to hollow vessels which are filled with air or any suitable gas by means of an air-compressor located above the surface of the water and a suitable connecting-pipe.

Now this invention relates to an improved hollow vessel which although it is very light in weight and is cheap to construct enables a comparatively large and perfectly constant 20 lifting power to be obtained and admits of the use of comparatively weak material in consequence of an automatic adjustment of the internal and external pressures.

Figure 1 of the accompanying drawings 25 shows a side elevation of such a hollow body. Figs. 2 and 3 are cross-sections corresponding, respectively, to the lines A B and C D of Fig. 1. Fig. 4 is a longitudinal section through the inner bag, which is gas and water tight. Figs. 5 and 6 show two methods of attaching the hollow body to the vessel, and Figs. 7 and 8 show details of the apparatus.

As will be seen from Figs. 1 to 4, the hollow body comprises an inflatable receptacle *a*, which is gas and water tight, and as it serves only for containing the air pumped in can be made of a comparatively thin and weak fabric or material. The inner receptacle *a* is inclosed in an outer envelop *b*, which 35 is made of a stronger fabric or material, such as sail-cloth, and prevents the receptacle *a* from expanding too much. It acts as a protecting device for the same, so that it does not require to be gas or water tight. For the 40 purpose of carrying the load a cover *c*, made of strong fabric or of netting, is placed around the envelop *b*, on the upperside thereof. This cover *c* is preferably provided on its lower edges with a hollow seam *d*, through which

there is drawn a rope *f* for the purpose of 50 strengthening it. Carrying-ropes *h* are drawn through holes *g* in the seam, and a large number of them are combined at the lower ends and passed through rings *i*, Fig. 1, or are arranged parallel to one another 55 and connected to a series of brackets, Fig. 6, or to longitudinal bars *e*, connecting the said brackets. Through the rings *i* there is passed a spar *j*, which facilitates the handling of the hollow body and enables it to be adjusted in 60 the horizontal plane. The spar *j*, which under certain circumstances has to stand a considerable bending strain, is made of a channel-iron beam *k* and two channel-shaped externally-rounded bars *l*, which are placed above 65 and below the said beam.

For the purpose of attaching the hollow body to the vessel or the like to be raised carriers *m*, Fig. 5, or brackets *m'*, Fig. 6, are preferably used and are placed so that the hollow 70 body does not come into contact with the side *n* of the ship. If it should be difficult to use such carriers, hooks may be attached to the sides of the ship, as shown in Fig. 8, by passing chains *p* and iron bars *q* through holes *o* 75 in the sunken ship and then bringing the iron bars into the position shown by drawing the chain tight.

For the purpose of forcing out the water in a uniform manner and effecting an automatic 80 adjustment of the pressures the following arrangement is used: As will be seen from Figs. 1, 2, 3, 4, and 6, the receptacle *a* is provided on its upper side with an air-inlet opening *r* and two air-outlet openings *s*, to the latter of 85 which flexible tubes *t*, extending almost to the bottom of the receptacle, are attached. At the lowest part of the receptacle *a* there are two water-outlets *u*. Of course the outer envelop *b* is provided with corresponding openings. The flexible pipe *v*, leading to the air-compressor or compressed-air reservoir, Figs. 1, 2, and 5, is attached to the opening *r*. Air entering at *r* forces out the water through the 90 openings *u*, so that the water-level in the receptacle *a* is gradually lowered until it reaches the lower ends of the tubes *t*. The water-level cannot sink lower, since the air can es- 95

cape through the tubes *t*. The quantity of water forced out depends on the length of the tubes *t*—that is to say, of the distance of the lower ends of these tubes from the bottom—and can be regulated by altering the length of these tubes according to the lifting power desired. For this purpose cords *w* are inserted in the tubes *t*, Figs. 3, 4, and 5, and are attached to the lower ends thereof, so that when these cords are drawn up the tubes are shortened or raised. When the external pressure decreases as the hollow body rises during the lifting, an automatic adjustment of the internal and external pressures takes place, since the air in the interior of the hollow body expands and escapes through the tubes *t*. The quantity of water forced out and the lifting power of the hollow body remain the same. The strain on the receptacle *a* is very slight in consequence of the automatic adjustment of the pressures. It is advantageous to make the receptacle somewhat larger in diameter than the outer envelop, so that the former will become corrugated when the outer envelop is expanded, Figs. 2, 3, and 6.

We claim—

1. In an apparatus for raising sunken objects, an inflatable receptacle provided with suitable inlets and outlets, tubes depending into said receptacle from said outlets, and means for adjusting said tubes.
2. In an apparatus for raising sunken objects, an inflatable receptacle provided with a suitable inlet and outlets, tubes depending into said receptacle from said outlets, means for adjusting said tubes, a supporting-cover, means for reinforcing the edges of said cover, a series of ropes connected to the cover, and means connected with the ropes for facilitating the handling and adjustment of the apparatus.
3. In an apparatus for raising sunken objects, an inflatable receptacle provided with suitable inlet and outlets, tubes depending into said receptacle from said outlets, means for adjusting said tubes, a supporting-cover mounted upon the receptacle, and means connected with the supporting-cover for attaching the apparatus to the object to be raised.
4. In an apparatus for raising sunken objects, a receptacle provided with suitable inlet and outlets, flexible tubes depending into

said receptacle from said outlets, and means for adjusting said tubes.

5. In an apparatus for raising sunken objects, a receptacle adapted to be inflated and provided with a suitable inlet, adjustable outlet-tubes depending into said receptacle, a cover mounted upon the receptacle, and means connected with the cover for attaching the apparatus to the object to be raised.

6. In an apparatus for raising sunken objects, a receptacle adapted to be inflated and provided with a suitable inlet, an envelop for the said receptacle, a cover mounted upon the envelop and provided with reinforced edges, adjustable outlet-tubes depending into said receptacle, and means connected with the cover for connecting the apparatus to the object to be raised.

7. In an apparatus for raising sunken objects, an inflatable inner receptacle, an outer envelop for limiting the expansion of the receptacle, a supporting-cover, ropes attached to the edges of said cover, and a spar connected with the ropes to facilitate the handling and adjustment of the apparatus.

8. In an apparatus for raising sunken objects, a receptacle provided with outlet-openings, and flexible air-outlet tubes depending from said outlets for determining the quantity of air contained in the apparatus and consequently its lifting power and enabling an automatic adjustment of the pressures to be obtained with a uniform displacement of the water.

9. In an apparatus of the character described, a receptacle, a cover therefor, means connected with the cover for attaching the apparatus to the object to be raised, and means connected to the receptacle for determining the quantity of air contained in the apparatus and consequently its lifting power, and enabling an automatic adjustment of the pressures to be obtained for a uniform displacement of the water.

In testimony whereof we have hereunto set our hands in presence of two subscribing witnesses.

MATIEU BOURHANOVSKY.
ALEXANDRE DE KOWANKO.
